Attorney

UNITED STATES PATENT OFFICE.

WILLIAM J. WALKER, OF BRADFORD, PENNSYLVANIA, ASSIGNOR OF ONE-SIXTH TO
ADDEN KEWLEY, OF BRADFORD, PENNSYLVANIA.

CUP FOR WORKING VALVES.

Application filed November 22, 1922. Serial No. 602,569.

To all whom it may concern:

Be it known that I, WILLIAM J. WALKER, a citizen of the United States, residing at Bradford, in the county of McKean and 5 State of Pennsylvania, have invented certain new and useful Improvements in Cups for Working Valves, of which the following is a specification, reference being had to the accompanying drawings.

10 This invention relates to cups for working valves used in well pumps.

It is an object of the invention to provide means whereby a cup of the working valve may be readily expanded.

15 It is another object of the invention to provide a device of this character wherein means are provided for expanding a cup of the working valve through the medium of pressure to protect the remaining cups of 20 the valve from wear due to enormous pressure.

With these and other objects in view, the invention consists in the improved construction and arrangement of parts to be hereinafter more particularly described, fully claimed and illustrated in the accompanying drawings, in which:

Figure 1 is a view in elevation of a working valve showing the invention applied;

30 Figure 2 is a sectional view of the device removed from the valve;

Figure 3 is a perspective view of the expanding rings; and

Figure 4 is a fragmentary elevation of another form of the invention.

35 Referring to the drawings, 5 designates a conventional form of working valve including a plurality of cups 6 of conventional form. It is well-known that these cups, in view of the enormous pressure, particularly at the bottom of the well, wear out in a short time, thus reducing the efficiency of the well, as well as interfering with protection.

40 In order to overcome this disadvantage there is provided a cup 7 which is constructed preferably of lead, reinforced with copper wire so that the cup will readily expand. This cup has a relatively large 45 central opening 8, the annular portion 9 of the bottom of the cup providing a seat for a purpose to be hereinafter described. The upper edge 10 of the cup is inwardly beveled.

50 In connection with the cup 7, a sleeve 11,

is provided, the lower edge portion 12 of the sleeve being rounded. The upper edge of the sleeve is provided with a flange 13. The upper edge of the sleeve at the junction of the flange with the sleeve is flared. 60

The sleeve is considerably longer than the cup so that the upper portion of the sleeve will extend a considerable distance above the cup. The lower end of the sleeve is intended to rest upon the seat 9 of the cup 65 7 and when so disposed the bore of the sleeve registers with the opening 8 to substantially form a continuation of the sleeve.

In order to expand the cup 7 during the working operation of the valve there is provided an expanding ring 14, said ring having its outer face 15 downwardly and inwardly beveled. The inner wall 16 of the ring is intended to engage the outer wall 70 of the sleeve 11.

75 In use, the cup 7 is intended to be applied to the working valve and the sleeve disposed within the cup. It is obvious that when the working valve is under pressure, for instance, when being drawn upwardly, that the ring 14 will be urged inwardly of the cup 7 in view of the beveled portion 10 of the cup 7 and beveled face 15 of the ring. This causes the cup 7, in view of its flexibility, to expand, and thus release the remaining cups 80 of the working valve from a greater portion of the pressure, thus increasing the efficiency of the device.

85 In Figure 4, another form of the invention is shown. This form consists in the application of a spring 17, one end of which is adapted to engage the upper face of the ring 14, while the opposite end is intended to engage the lower face of the flange 13. The purpose of the spring is to assist in 90 urging the expanding ring 14 inwardly of the cup 7.

95 From the foregoing it will be readily seen that this invention provides a novel form 100 of expanding cup for working valves capable of being used in connection with the working valve of any pump, regardless of the material discharged by the pump. In addition to this it provides a novel cup which is expandable and retractable according to the movement of the working valve. This is made possible by the reinforcing copper wire and the lead used in the formation of the cup. In view of the substantially 105 wedge-shaped formation of the expanding 110

ring it will be an easy matter for the ring to expand the cup when pressure is applied to the ring during movement of the working valve, and when the movement of the valve is reversed, the ring will be readily moved outwardly of the cup to permit the cup to adjust itself. All of these features are possessed by a device which is simple in construction and compact in form and which is capable of being applied to the conventional forms of working valves.

What is claimed is:—

1. In a cup structure for working valves including a piston, a cup arranged upon the piston formed of soft metal reinforced with a harder metallic wire and adapted to be expanded, a sleeve on the piston engaging the bottom portion of the cup and a spring pressed ring slidable upon the sleeve and having a beveled surface engaging within

the open end of the cup whereby to expand the same.

2. A cup for working valves including a piston, comprising a cup of lead having reinforcing wire imbedded therein, said cup having its bottom portion formed with an opening through which the piston passes, the flange of the cup flaring outwardly from the bottom thereof, a sleeve on the piston fitting against the inside of the bottom of the cup, and a spring pressed ring slidable on the sleeve and having a beveled surface engaging within the open upper end of the cup.

3. A cup for working valves formed of lead having copper wire imbedded therein. In testimony whereof I hereunto affix my signature.

WILLIAM J. WALKER.
